LOW-PASS FILTER SYSTEM

Gordon L. Fredendall, Feasterville, Pa., assignor
to Radio Corporation of America, a corporation
of Delaware

Application November 29, 1943, Serial No. 512,115

13 Claims. (Cl. 178—44)

1 This invention relates generally to wave transmission networks and more particularly to adjustable low-pass networks employing a plurality of fixed filter circuits.

Heretofore, adjustable low-pass filters having a continuously variable cut-off frequency have included a plurality of individually adjustable reactive filter components. Adjustable reactive elements, suitable for low-pass networks, are costly and cumbersome. It also is costly and inconvenient to gang a large number of adjustable reactive elements for convenient unitary adjustment of the cut-off frequency.

The instant invention contemplates broadly converting the currents of one frequency into currents of a higher frequency. The higher frequency currents are applied to a low-pass network employing only two fixed reactive filter networks in combination with two fixed modulators and two adjustable carrier frequency sources such as, for example, thermionic tube oscillators. The two fixed filter networks have frequency band-pass characteristics at frequencies related to but appreciably higher than the desired low-pass cut-off frequency. The conversion to higher frequencies reduces the physical size and cost of the filter components.

The signal frequency currents which are to be attenuated are applied to a first carrier frequency from one of the oscillator circuits to provide two equal side bands. The two side bands and the first carrier frequency are applied to the first filter network to attenuate only the upper side band to the desired low-pass band width. The unequally attenuated side bands and the first carrier are then applied to the second carrier frequency which is selected to be substantially higher than the first carrier frequency. The second fixed filter network has a pass band which attenuates the lower part of the upper band side band to a value substantially equal to the upper part of the upper band side band, thereby providing a high frequency carrier having two side bands each having widths equivalent to the desired low-pass band. The high frequency modulated carrier is applied to a demodulator or envelope detector to derive the low-pass frequency band desired.

Among the objects of the invention are to provide an improved method of and means for transmitting a predetermined low-pass frequency band. Another object of the invention is to provide an improved low-pass transmission network employing relatively high frequency band-pass filter net-

works. An additional object of the invention is to provide an improved adjustable low-pass transmission network employing a plurality of fixed band-pass filter networks.

5 A further object of the invention is to provide an improved adjustable low-pass transmission network employing in combination a plurality of fixed filter networks, a plurality of adjustable carrier frequency sources and means for modulating the signal frequencies with the carrier frequency sources to provide the desired low-pass frequency transmission band.

The invention will be further described by reference to the accompanying drawing of which 15 Figure 1 is a schematic circuit block diagram of a preferred embodiment, Figure 2 is a family of graphs indicating the operation of the circuit of Figure 1, Figure 3 is a schematic circuit diagram of a typical fixed band-pass filter network forming one of the elements of the circuit of Figure 1 and Figure 4 is a graph illustrative of the frequency band-pass characteristics of filter networks of the type described in Figure 3. Similar reference characters are applied to similar elements throughout the drawing.

20 Referring to Figure 1 of the drawing, a source of signals occupying a frequency band from zero to a frequency f_1 is applied to the input circuit of a first thermionic tube modulator 3. A source of carrier frequency currents such as, for example, a thermionic tube oscillator 5 also is connected to the input circuit of the first modulator 3 to provide modulated carrier currents in the output circuit of the modulator 3. If the frequency f_{c1} 25 of the first carrier frequency oscillator 5 is appreciably higher than the highest signal frequency f_1 , the currents derived from the first modulator will include a carrier and sidebands covering a frequency spectrum from $(f_{c1}-f_1)$ to $(f_{c1}+f_1)$.

30 This frequency spectrum is applied to the input of a fixed band-pass filter network having a pass band $(f_{c1}-f_1-\Delta f)$ to $(f_{c1}+\Delta f)$. It will be seen that the lower sideband $(f_{c1}-f_1)$ will not be attenuated by the band-pass filter 7 while the upper sideband $(f_{c1}+f_1)$ will be attenuated to a value $(f_{c1}+\Delta f)$. The currents derived from the 35 first band-pass filter 7 are applied to the input circuit of a second thermionic tube modulator 9. The output of a second carrier frequency source such as, for example, a thermionic tube oscillator 11 having a carrier frequency f_{c2} , is also applied to the input of the second modulator 9. The modulated carrier derived from the second modulator 40

9 will include carrier and sidebands covering the spectra $(fc_2 - fc_1) - f_2$ to $(fc_2 - fc_1) + f_1$ and $(fc_2 + fc_1) - f_1$ to $(fc_2 + fc_1) + f_2$. These two sidebands and the second carrier frequency fc_2 are applied to the input of a second bandpass filter network having a pass band covering the spectrum $(fc_2 + fc_1) - f_2$ to $(fc_2 + fc_1) + f_2 + \Delta f$. It will be seen that the second band-pass filter will attenuate the lower portion of the upper sideband to a band width equivalent to f_2 , and will not affect the transmission of the upper portion of the upper sideband which already has a band width of f_2 . Therefore, the output of the second band-pass filter 13 will comprise frequencies covering the spectrum $(fc_2 + fc_1) - f_2$ to $(fc_2 + fc_1) + f_2$ or, 15 in other words, a carrier $(fc_2 + fc_1)$ having equal upper and lower sidebands f_2 .

The output of the second band-pass filter 13 is applied to a demodulator 15 such as, for example, a diode thermionic tube, to derive currents covering the frequency spectrum from zero to f_2 , which is the desired low frequency spectrum from 20 zero to f_2 , which is the desired low frequency pass band.

If it is desired to derive a pass band from zero to a frequency f_3 where $f_3 < f_2 < f_1$, it merely is necessary to increase the frequency of the first carrier frequency fc_1 to a value $(fc_1 + f_2 - f_3)$ and simultaneously as indicated by the dash line 33 of Fig. 1, to decrease the second carrier frequency 30 fc_2 to $[fc_2 - 2(f_2 - f_3)]$. Similarly, if it is desired to increase the pass band, the first carrier fc_1 will be decreased in frequency and the second carrier fc_2 will be increased in frequency in the same manner as described heretofore.

In Figure 2, graph a indicates the original signal frequency band 0 to f_1 and the desired low-pass band 0 to f_2 . The first carrier frequency is indicated by the dash line fc_1 and the output currents derived from the first modulator are indicated by the frequency spectrum $(fc_1 - fc_1)$ to $(fc_1 + f_1)$.

Graph b indicates the band-pass characteristics of the first and second band-pass filters. Graph c indicates the output currents derived from the first filter network showing the attenuation of the upper sideband $(fc_1 + f_1)$ to a value f_2 .

Graph d illustrates the second carrier frequency, indicated by the dash line fc_2 , and the upper and lower sidebands provided by the modulation of the second carrier by the modulated first carrier. Graph e illustrates the attenuation of the lower portion of the upper sideband and the lack of attenuation of the upper portion of the upper sideband whereby two equal sidebands having a band width f_2 and a carrier $(fc_2 + fc_1)$ are obtained from the second filter network. As explained heretofore, the currents illustrated by the graph e are applied to the demodulator 15 to derive the desired low frequency pass band.

The fixed band-pass filter networks 7, 13 may be of any conventional type known in the art which will provide the desired frequency band-pass spectra and permissible phase distortion. A typical band-pass filter network is illustrated schematically in Figure 3 and includes a first resonant circuit 17 comprising a parallel-connected inductor 19 and capacitor 21 coupled through coupling capacitors 23, 25 to a second resonant circuit 27 comprising a parallel-connected inductor 29 and capacitor 31. The parallel 70 resonant circuits 17, 27 may be tuned to the same or slightly different resonant frequencies, and, if desired, the inductors 19, 29 may be inductively as well as capacitively coupled. Likewise, the coupling between the resonant circuits 17, 27 may 75

be entirely inductive and the coupling capacitors 23, 25 omitted.

Figure 4 illustrates a typical response curve for a band-pass filter of the type described in Figure 3 wherein substantially uniform attenuation is provided at all frequencies except those within a predetermined frequency band wherein extremely low attenuation; i. e., good transmission is provided for the desired applied signal currents.

It should be understood that any other known types of band-pass filter networks may be substituted for the type described in Figure 3, and that phase distortion of the signal may be minimized to any desired extent by applying Bode's theory to the design of linear phase shift filters in each of the band-pass filter networks. The advantages of the low-pass network thus described are particularly outstanding if an adjustable network providing low phase distortion of the signal is desired. Adjustable low-pass filters, having a variable cut-off frequency, designed according to Bode's theory, would require the ganging of numerous variable capacitors and inductors.

Thus the invention described comprises an improved means for and method of securing low band-pass transmission of signal frequency currents by conversion of low frequencies to higher frequencies and by employing relatively high frequency band-pass filters in combination with conventional thermionic tube modulators and adjustable thermionic tube oscillators. After the required frequency conversions and attenuations, the original signal frequencies, less the undesired frequencies, are obtained by demodulation. In the described system relatively simple frequency changes bring about the desired band-pass characteristics instead of changing the reactive characteristic of band-pass filters, which reactive changes are usually accompanied with undesired phase shifts.

I claim as my invention:

1. Apparatus for providing low band pass transmission of signal frequency currents including means for deriving from said signal currents second currents having a carrier and two sidebands, one of said sidebands having the desired frequency band width, means for deriving from said second currents third currents having a second carrier and two equal second sidebands each having the desired frequency band width, and detection and filter means for demodulating said third currents to derive fourth currents having substantially only frequencies within said desired low pass band.

2. Apparatus for providing adjustable low band pass transmission of signal frequency currents including means for deriving from said signal currents second currents having a carrier and two sidebands, one of said sidebands having the desired frequency band width, means for deriving from said second currents third currents having a second carrier and two equal second sidebands each having the desired frequency band width, means for adjusting the carrier frequency upon which each of said sidebands depend, and detection and filter means for demodulating said third currents to derive fourth currents having substantially only frequencies within said desired low pass band.

3. A low band pass network for a source of signal frequency currents including a pair of modulators, a pair of carrier current sources having different carrier frequencies, a pair of filter networks each capable of transmitting a band of frequencies including a different one of said

carrier frequencies, means including one of said modulators responsive to said signal source and to one of said carrier current sources for deriving from one of said filter networks said one carrier and two sidebands, one of said sidebands having the desired low pass band width, means including said other modulator and said other filter network responsive to said frequencies derived from said one filter and said other carrier source for deriving currents of said other carrier and two equal second sidebands each having said desired low pass band width, and means for detecting said last mentioned equal sidebands to derive currents having substantially only frequencies within said desired low pass band.

4. An adjustable low band pass network for a source of signal frequency currents including a pair of modulators, a pair of carrier current sources having adjustable different carrier frequencies, a pair of filter networks each capable of transmitting a band of frequencies including a different one of said carrier frequencies, means including one of said modulators responsive to said signal source and to one of said carrier current sources for deriving from one of said filter networks said one carrier and two sidebands, one of said sidebands having the desired low pass band width, means including said other modulator and said other filter network responsive to said frequencies derived from said one filter and said other carrier source for deriving currents of said other carrier and two equal second sidebands each having said desired low pass band width, means for adjusting the frequencies of said carrier current sources, and means for detecting said last mentioned equal sidebands to derive currents having substantially only frequencies within said desired low pass band.

5. An adjustable low band pass network for a source of signal frequency currents including a pair of modulators, a pair of carrier current sources having adjustable different carrier frequencies, a pair of filter networks each capable of transmitting a band of frequencies including a different one of said carrier frequencies, means including one of said modulators responsive to said signal source and to one of said carrier current sources for deriving from one of said filter networks said one carrier and two sidebands, one of said sidebands having the desired low pass band width, means including said other modulator and said other filter network responsive to said frequencies derived from said one filter and said other carrier source for deriving currents of said other carrier and two equal second sidebands each having said desired low pass band width, means for adjusting simultaneously the frequencies of said carrier current sources, and means for detecting said last mentioned equal sidebands to derive currents having substantially only frequencies within said desired low pass band.

6. A low band pass network for a source of signal frequency currents including a first modulator, a first carrier frequency current source, a first band pass filter network, means for applying currents including currents of frequencies to be transmitted and said first carrier currents to said first modulator to derive said first carrier and equal sideband currents, means for applying said equal sideband currents to said first filter to pass said first carrier, a complete one of said sidebands and only the desired low frequency portion of the other of said sidebands, a second carrier frequency current source, a second modulator,

means for applying said second carrier currents and said first carrier and sideband currents derived from said first filter to said second modulator to derive said second carrier and second equal second sideband currents, a second band pass filter network, means for applying said second carrier and said second equal sideband currents to said second filter to derive two equal sidebands each having widths corresponding to said desired low frequency portion of said other of said first sidebands, and means for detecting said last mentioned equal sidebands to derive currents having substantially only frequencies within the desired low pass band.

7. An adjustable low band pass network for a source of signal frequency currents including a first modulator, a first adjustable carrier frequency current source, a first band pass filter network, means for applying currents including currents of frequencies to be transmitted and said first carrier currents to said first modulator to derive said first carrier and equal sideband currents, means for applying said equal sideband currents to said first filter to pass said first carrier, a complete one of said sidebands and only the desired low frequency portion of the other of said sidebands, a second adjustable carrier frequency current source, a second modulator, means for applying said second carrier currents and said first carrier and sideband currents derived from said first filter to said second modulator to derive said second carrier and second equal sideband currents, a second band pass filter network, means for applying said second carrier and second equal sideband currents to said second filter to derive two equal sidebands each having widths corresponding to said desired low frequency portion of said other of said first sidebands, means for adjusting the frequencies of said carrier current sources, and means for detecting said last mentioned equal sidebands to derive currents having substantially only frequencies within the desired low pass band.

8. An adjustable low band pass network for a source of signal frequency currents including a first modulator, a first adjustable carrier frequency current source, a first band pass filter network, means for applying currents including currents of frequencies to be transmitted and said first carrier currents to said first modulator to derive said first carrier and equal sideband currents, means for applying said equal sideband currents to said first filter to pass said first carrier, a complete one of said sidebands and only the desired low frequency portion of the other of said sidebands, a second adjustable carrier frequency current source, a second modulator, means for applying said second carrier currents and said first carrier and sideband currents derived from said first filter to said second modulator to derive said second carrier and second equal sideband currents, a second band pass filter network, means for applying said second carrier and second equal sideband currents to said second filter to derive two equal sidebands each having widths corresponding to said desired low frequency portion of said other of said first sidebands, means for adjusting simultaneously the frequencies of said carrier current sources, and means for detecting said last mentioned equal sidebands to derive currents having substantially only frequencies within the desired low pass band.

9. The method of providing low band pass transmission of signal frequency currents comprising generating first carrier currents, modu-

modulating said first carrier currents by applying thereto said signal currents, selecting a predetermined frequency portion including the carrier and at least portions of both sidebands of said modulated carrier currents, generating second carrier currents of a frequency different than said first carrier currents, modulating said second carrier currents by applying thereto said selected modulated carrier currents, selecting a predetermined portion of said last mentioned modulated carrier currents, and detecting said selected portion of the last mentioned carrier currents to derive signal currents having substantially only frequencies within said desired low pass band.

10. The method of providing adjustable low band pass transmission of signal frequency currents comprising generating first carrier currents, modulating said first carrier currents by applying thereto said signal currents, selecting a predetermined frequency portion including the carrier and at least portions of both sidebands of said modulated carrier currents, generating second carrier currents of a frequency different than said first carrier currents, modulating said second carrier currents by applying thereto said selected modulated carrier currents, selecting a predetermined portion of said last mentioned carrier currents, adjusting the frequencies of said first and said second carrier currents, and detecting said selected portion of said last mentioned carrier currents to derive signal currents having substantially only frequencies within said desired low pass band.

11. The method of providing adjustable low band pass transmission of signal frequency currents comprising generating first carrier currents, modulating said first carrier currents by said signal currents, selecting a predetermined frequency portion including the carrier and at least portions of both sidebands of said modulated carrier currents, generating second carrier currents of a frequency different than said first carrier currents, modulating said second carrier currents by said selected modulated carrier currents, selecting a predetermined portion of said last mentioned carrier currents, adjusting simultaneously the frequencies of said first and said second carrier currents, and detecting said selected portion of said last mentioned carrier currents to derive signal currents having substantially only frequencies within said desired low pass band.

12. The method of providing adjustable low band pass transmission of signal frequency currents comprising generating first carrier currents, modulating said first carrier currents by said signal currents, selecting a predetermined frequency portion including the carrier and at least portions of both sidebands of said modulated currents, generating second carrier currents of a frequency different than said first carrier currents, modulating said second carrier currents by said selected modulated carrier currents, selecting a predetermined portion of said last mentioned carrier currents, adjusting the frequency of said first carrier currents and said second carrier currents in opposite senses, and detecting said selected portion of said last mentioned carrier currents to derive signal currents having substantially only frequencies within said desired low pass band.

13. The method of providing adjustable low band pass transmission of signal frequency currents comprising generating first carrier currents, modulating said first carrier currents by said signal currents, selecting a predetermined frequency portion including the carrier and at least portions of both sidebands of said modulated currents, generating second carrier currents of a frequency different than said first carrier currents, modulating said second carrier currents by said selected modulated carrier currents, selecting a predetermined portion of said last mentioned carrier currents, adjusting the frequency of said first carrier currents and said second carrier currents in opposite senses and in different proportionate amounts and detecting said selected portion of said last mentioned carrier currents to derive signal currents having substantially only frequencies within said desired low pass band.
